United States Patent Office

Des. 214,933
Patented Aug. 12, 1969

214,933

DESSERT DISH OR THE LIKE

James B. Swett, Barrington, R.I., and Thomas E. Brown, Birmingham, Mich., assignors to Dart Industries Inc., a corporation of Delaware

Filed Aug. 12, 1968, Ser. No. 13,119

Term of patent 14 years

Int. Cl. D7—01

U.S. Cl. D44—9

We claim:

The ornamental design for a dessert dish or the like, as shown and described.
